UNITED STATES PATENT OFFICE.

JOHN P. MONGAN, OF MINNEAPOLIS, MINNESOTA.

LOCOMOTIVE-BOILER.

1,385,386.

Specification of Letters Patent. Patented July 26, 1921.

Application filed August 22, 1918. Serial No. 251,023.

To all whom it may concern:

Be it known that I, JOHN P. MONGAN, a citizen of the United States, residing at Minneapolis, in the county of Hennepin and

5 State of Minnesota, have invented certain new and useful Improvements in Locomotive-Boilers; and I do hereby declare the following to be a full, clear, and exact description of the invention, such as will enable others skilled in the art to which it appertains to make and use the same.

10 My invention relates particularly to locomotive boilers, but more generally to horizontal flue boilers, and has for its object to 15 provide simple and efficient means whereby superheated steam or steam that is very dry, may be produced without requiring a radical change in or addition to boilers already in use. Generally stated, the invention consists of the novel devices and combinations 20 of devices hereinafter described and defined in the claims.

25 In accordance with my invention, I place within the boiler, preferably a short distance ahead of the fire box, a so-called baffle plate through which the flues are passed. This baffle plate divides the front and rear portion of the boiler into different compartments. The baffle plate is perforated at its 30 upper portion so that the pressure will be applied in the front and rear portions of the boiler, and in such manner that the altitude of the water in the rear portion of the boiler will be maintained always above the top of 35 the fire box while the altitude of the water in the front portion of the boiler may be maintained at somewhat constant, but varying level below the uppermost flues. This arrangement permits portions of the upper 40 flues to be exposed in the front compartment of the boiler above the water level, so that they will become very hot and will superheat the steam in the front portion of the boiler. Also, with this arrangement, it is 45 advisable to bring the dome forward and locate the same above the front compartment of the boiler.

50 The invention is illustrated in the accompanying drawings wherein like characters indicate like parts throughout the several views. Referring to the drawings,

Figure 1 is a vertical section taken centrally through a boiler designed in accordance with my invention, some parts being broken away;

55 Fig. 2 is a transverse vertical section taken

on the line 2—2 of Fig. 1; Fig. 3 is a fragmentary side elevation of the boiler; and Fig. 4 is a detail view in section of the check-valve-equipped connection.

60

Of the parts of the boiler, the numeral 3 indicates the fire box; the numeral 4 that portion of the boiler that incloses the fire box and within which the so-called rear compartment of the boiler is located; the numeral 5 the front portion of the boiler equipped with a dome 6, and at its front end leading to a smoke compartment 7; and the numeral 8 indicates the flues which, in the usual way, extend from the fire box to the smoke compartment.

65

70 In accordance with my invention, the so-called baffle plate 9 is located within the shell of the boiler and secured with a water tight joint. All of the flues 8 extend through this 75 baffle plate and they should be expanded so as to form water tight joints therewith. The arrangement of perforations in the upper portion of the baffle plate may vary, but as shown, is provided with upper steam passages or perforations 10 and with lower overflow passages or perforations 11. The perforations 11 are located on an altitude above all of the flues and above the top of the fire box and they determine the altitude 85 of the water y which is within the rear compartment of the boiler. The upper perforations 10 insure always equalizations of pressure in the front and rear compartments of the boiler.

80

90 In this arrangement, the water must be delivered into the rear compartment of the boiler or back of the baffle plate 9, and, as shown, this will be accomplished through a check-valve-equipped connection 13 leading 95 from any suitable water supply. To enable an engineer, from within the cab, in keeping track of the water level in the front compartment of the boiler, a pipe 14 leads from the top of the rear compartment of the boiler 100 and is tapped into the front compartment of the boiler, considerably below the water level, and has interposed therein a gage at the normal water level in said front compartment. Of course, the water level in the 105 rear compartment of the boiler may be maintained in any suitable way, not necessary for the purpose of this case to further consider.

With this arrangement, the level of the water y^1 in the front compartment of the boiler will be kept somewhere not far from the level indicated in Fig. 1. Obviously,

95

100

105

110

those flues 8 that are above the level of the water y^1 and forward of the baffle plate 9, will be exposed in the steam contained within the front compartment of the boiler and 5 will be made very hot by the flames that are passed therethrough. Otherwise stated, they will be heated up very much like the flues of a superheater, and the effect on the steam in the front compartment in the boiler will 10 be very much like that of a superheater, that is, the steam will be made much drier than in the ordinary boiler.

By this arrangement, dry steam is produced in the most efficient way and economy 15 of fuel is thereby effected. Moreover, it is not a difficult matter to convert an ordinary locomotive boiler into a boiler of the type involved in my invention.

What I claim is:

20 1. A combination with a boiler of the locomotive type, of a baffle plate applied within the boiler forward within the rear end of the flues and through which the flues are passed to the flue sheet of the fire-box, said 25 baffle plate having a water passage above the level of the flues and above the top of the fire-box, whereby a higher level of water may be maintained in the rear compartment of the boiler than in the front compartment 30 of said boiler, all of said flues being covered

with water at the rear of said baffle plate, but certain of the upper flues, forward of said baffle plate, being above the water level in the front compartment of the boiler, so that they will be exposed in the steam chamber thereof. 35

2. A combination with a boiler of the locomotive type, of a baffle plate applied within the boiler forward within the rear end of the flues and through which the flues are 40 passed to the flue sheet of the fire-box, said baffle plate having a water passage above the level of the flues and above the top of the fire-box, whereby a higher level of water may be maintained in the rear compartment 45 of the boiler than in the front compartment of said boiler, all of said flues being covered with water at the rear of said baffle plate, but certain of the upper flues, forward of said baffle plate being above the water level 50 in the front compartment of the boiler, so that they will be exposed in the steam chamber thereof, and a steam dome applied to the top of the front compartment of the boiler.

In testimony whereof I affix my signature 55 in presence of two witnesses.

JOHN P. MONGAN.
